UNITED STATES PATENT OFFICE.

AMOS B. ROOT AND JAMES F. YOUTZ, OF MOUNT JOY, PENNSYLVANIA.

ADJUSTABLE PLOW-SHOVEL.

SPECIFICATION forming part of Letters Patent No. 357,788, dated February 15, 1887.

Application filed February 12, 1886. Serial No. 191,768. (No model.)

To all whom it may concern:

Be it known that we, AMOS B. ROOT and JAMES F. YOUTZ, of Mount Joy, in the county of Lancaster and State of Pennsylvania, have 5 invented a new and Improved Adjustable Plow-Shovel, of which the following is a full, clear, and exact description.

Our invention will first be described, and then specifically pointed out in the claims.

Reference is to be had to the accompanying drawings, forming a part of this specification, in which similar letters of reference indicate corresponding parts in all the figures.

Figure 1 is a view of a portion of a cultivator provided with our improved adjustable shovel, the bracket of the forward standard, however, being shown in connection with an ordinary bull-tongue shovel. Fig. 2 is a sectional view of the lower portion of the standard. Fig. 3 is a view of the shovel-supporting bracket, the lower portion of the same being shown in section. Fig. 4 is a face view of the bracket. Fig. 5 is a plan view of the same. Fig. 6 is a face view of a pillow-block placed 25 upon the face of the bracket when said bracket is used to support the bull-tongue shovel, and Fig. 7 is a view in vertical section of the said pillow-block.

In the drawings, A represents the frame of an ordinary form of cultivator, and B one of the side beams of such frame, to which beam there are secured the standards C and D, the main connection between the parts being made by means of a pivot-bolt, a, and an adjusting-bolt, a', which is passed through one of the apertures i i at the forward end of the standard. The lower ends of the standards are socketed at b to receive the thimble E, the lower edge of which is provided with teeth d d. Within the socket of this thimble there is fitted the shank e of the bracket F, to which the shovel G is bolted, a groove, f, being formed near the upper end of the shank e, so that when the shank is inserted within the 40 socket it may be held in place by a set-screw, H, which passes through the threaded socket formed in the side of the standard and also through the aperture formed in the thimble E. Just at the foot of the shank e there is a catch 45 tooth or lug, g, arranged to enter the spaces between the teeth d, which teeth, as before stated, extend around the lower edge of the thimble E, so that when the shank e is inserted

within the socket of the thimble E and turned to the required angle it will be securely held 55 in position, the union between the parts being practically rigid.

In certain cases it is desirable that the broad-faced shovels G should be removed and a vertical form of bull-tongue shovel substituted therefor; but at this time it is desirable that the lower edge, n, should be tilted forward, so that after removing the shovel G, I prefer to introduce a pillow-block, M, between the bracket F and the shovel N, said pillow-block being much thicker at its lower than at its upper edge, being provided with a lug, k, arranged to enter the lower bolt-hole of the bracket or shovel N, and being secured and held in position by a bolt, l; as shown in Fig. 1. 65

Although I have illustrated and described a standard the lower end of which was socketed to receive a tooth-edged thimble, it will of course be understood that the thimble might be omitted and the teeth d d formed 75 upon the lower edge of the standard itself.

Having thus fully described our invention, what we claim as new, and desire to secure by Letters Patent, is—

1. The curved standard having a pivot and 80 adjusting-apertures at its upper end and the vertical socket at its lower end, the transverse screw H, extending into said socket, and the bracket F, formed with the vertical shank e, having the annular groove into which the set-screw enters to hold said shank from horizontal 85 or vertical movement, substantially as set forth.

2. The combination, with the standard having the vertical socket b in its lower end, the thimble E, having a flange resting against the socketed end of the standard and having serrations d, and the horizontal set-screw passed through the walls of the socket and the thimble, of the bracket F, formed with a vertical 95 shank, e, entering the socket and having an annular groove, f, to receive the end of the set-screw, and a tooth, g, at the base of the shank to engage the serrated flange of the thimble, substantially as set forth.

AMOS B. ROOT.
JAMES F. YOUTZ.
